Primary Examiner — Mimosa De(74) *Attorney, Agent, or Firm* — Cook Alex Ltd.; R. Blake Johnston(57) **CLAIM**

The ornamental design for a chair, as shown and described.

DESCRIPTION

FIG. 1 is a perspective view of the chair;
 FIG. 2 is a front elevational view of the chair;
 FIG. 3 is a rear elevational view of the chair;
 FIG. 4 is a left side elevational view of the chair, the opposite side of which is a mirror image;
 FIG. 5 is a top plan view of the chair; and,
 FIG. 6 is a bottom plan view of the chair.
 The dashed lines shown in the drawings illustrate stitching, which forms a part of the claimed design.
